UNITED STATES PATENT OFFICE.

SAMUEL V. REEVES, OF HADDONFIELD, NEW JERSEY.

SEDIMENT TRAP.

Application filed July 15, 1924. Serial No. 726,233.

To all whom it may concern:

Be it known that I, SAMUEL V. REEVES, a citizen of the United States, residing at Haddonfield, county of Camden, State of New Jersey, have invented a new and useful Sediment Trap, of which the following is a specification.

The object of this invention is to devise a novel construction and arrangement of a sediment trap for hot water heating systems which can be economically manufactured and which will collect and retain the sediment, provision being made for draining off such sediment when desired.

With the above and other objects in view, my invention comprehends a novel construction and arrangement of a sediment trap.

It further comprehends a novel sediment trap having an inlet and an outlet with a plurality of baffles therebetween, and having a sediment collecting chamber in direct and preferably valve controlled communication with the passages between certain of said chambers.

It further comprehends a trap of the character described wherein the walls of the sediment collecting chamber converge upwardly to direct the valve towards its seat.

Other novel features of construction and advantage will hereinafter more clearly appear in the detailed description and the appended claims.

For the purpose of illustrating the invention, I have shown in the accompanying drawing a typical embodiment of it, which, in practice, will give reliable and satisfactory results. It is, however, to be understood that this embodiment is typical only and that the various instrumentalities of which my invention consists can be variously arranged and organized, and that the invention is not limited to the precise arrangement and organization of these instrumentalities as herein set forth.

Figure 1 is a top plan view of a sediment trap embodying my invention.

Figure 2 is a section on line 2—2 of Figure 1.

Similar numerals of reference indicate corresponding parts.

Referring to the drawings:

1 designates a casting which forms the casing of a sediment trap embodying my invention.

2 The casing is provided with two openings 2 and 3 respectively which are internally

threaded and either of which may serve as the inlet or the outlet. These openings are preferably diametrically opposite each other. The upper central portion is preferably of rectangular contour to provide a comparatively wide water chamber, within which are a plurality of baffles, and, as illustrated, I have shown the baffles 4, 5 and 6 thereby forming the vertically disposed and parallelly arranged water passages 7, 8, 9 and 10 respectively. The bottoms of these passages are preferably curved and juxtaposed passages communicate with each other either at their top or at their bottom.

As illustrated and in one embodiment of the invention, the baffles 4 and 6 terminate a desired distance from the top wall 11, and the intermediate baffle 5 terminates a desired distance from the bottom wall 12.

The chamber 13 communicates by means of a port 14 with the sediment collecting chamber 15, and this port 14 has its lower edge portion forming a seat 16 for a valve 17, preferably in the form of a ball. The upper walls 80 of the sediment chamber converge or incline towards the seat 16 as shown at 18 so that the tendency of the valve 17 is to move towards its seat, as the chamber 15 is full of water. The casing 19 of the sediment chamber is 85 preferably rounded as shown and at its bottom in alignment with the seat 16, is a drainage outlet 20, which is of greater diameter than the valve in order that such valve can be inserted into and removed from the 90 chamber 15. This outlet is provided with a closure 21 which may be in the form of a valve controlled fitting or union 21, as shown in Figure 2. The casing is provided with the bosses 22 and 23 respectively.

The operation of the sediment trap will now be clear to those skilled in this art.

The trap is connected in the water line so that either the opening 2 or the opening 3 forms the inlet.

Assuming for the purpose of explanation that the opening 2 is the inlet, the water travels upwardly through the passage 7, over the baffle 4, downwardly through the passage 8 around the baffle 8, upwardly 105 through the passage 9 over the baffle 6 and downwardly through the passage 10 to the outlet 3. The sediment and foreign material carried by the water passes into the chamber 13 and into the port 14, and gradually works 110 by the valve 17 and is collected in the sediment chamber 15. The specific gravity of

nearly all of the sediment is greater than that of the water and more sediment is deposited or precipitated in a given number of inches of vertical travel than would be 5 possible in the horizontal travel of the water over the same distance. While I preferably employ the valve 17, this can, if desired, be omitted.

In practice the passages or chambers 7, 8, 10 9 and 10 are substantially the same in height as in width.

The curvature or inclination of the upper wall of the sediment chamber is such as to cause the ball to rest against the seat 16.

15 As the pressure is equal on all walls of a vessel, the ball float will, when the water is agitated by thermostatic pressure, prevent the sediment being carried up into the circulating chamber, thereby preventing the dis- 20 coloration of the water.

The agitating of the water, when boiling, causes sufficient movement of the ball valve to permit the precipitation of the sediment to the sediment receiving chamber 15. The 25 valve float may be made solid or hollow and of any material which is lighter than water.

The drainage outlet can lead to any desired point of discharge, and the controlling valve can be on the bell casing 19, the fitting 21 or the discharge line for the drainage.

Whenever circumstances require, the valve, can be opened and the sediment drained off.

The entire trap, except the valve and the 35 closure for the sediment chamber, is preferably cast in a single casting.

It will be apparent to those skilled in this art that my present invention takes up but a minimum space and can be very economically manufactured. It can also be installed by unskilled labor as it can be placed in the water line with either a right hand or a left hand arrangement, since it is immaterial whether the opening 2, for example, serves 45 as an inlet or an outlet.

It will also be apparent that any desired number of baffles may be employed between the intermediate baffle and the inlet and the outlet, and thus increase the length of travel 50 of the water. The casing which contains the circulating chamber may also be extended in height or in width or both, as occasion may

demand. The baffles are preferably vertically disposed, or they may extend at any desired angle relatively to the direction of 55 flow through the inlet and the outlet, or with respect to the bottom of the circulating chamber.

It will now be apparent that I have devised a new and useful sediment trap for 60 hot water heating systems which embodies the features of advantage enumerated as desirable in the statement of the invention and the above description, and while I have, in the present instance, shown and described 65 a preferred embodiment thereof which will give in practice satisfactory and reliable results, it is to be understood that this embodiment is susceptible of modification in various particulars without departing from 70 the spirit or scope of the invention or sacrificing any of its advantages.

Having thus described my invention, what I claim as new and desire to secure by Letters Patent, is:

1. A sediment trap comprising a casing 75 having openings at opposite sides, either of which may serve as an inlet, and having an internal chamber forming a circulating chamber in communication with said openings 80 and separated by baffles extending upwardly above said inlet and outlet and by a baffle extending downwardly, said baffles forming a plurality of vertically disposed communicating passages in said circulating chamber, 85 said casing having a sediment chamber below said circulating chamber and communicating therewith, and provided with a drainage outlet, and means to control said outlet. 90

2. A sediment trap comprising a casing 95 having an inlet and an outlet, and having a circulating chamber communicating with said inlet and outlet and formed by baffles certain of which extend from the bottom of said chamber above said inlet and said outlet, said casing having a sediment chamber at its lower portion communicating by a port with said circulating chamber, the upper walls of said sediment chamber converging towards said port, and a float valve in 100 said sediment chamber which tends to move towards said port, due to the converging walls of said sediment chamber.

SAMUEL V. REEVES.
